(57) **CLAIM**

The ornamental design for a camera, as shown and described.

DESCRIPTION

FIG. 1 is a perspective view of a camera showing our new design tilted at a first position;

FIG. 2 is a front view thereof;

FIG. 3 is a left side view thereof, a right side view being a mirror image of the left side view;

FIG. 4 is a top view thereof;

FIG. 5 is a bottom view thereof;

FIG. 6 is a perspective view thereof tilted at a second position; and,

FIG. 7 is a perspective view thereof tilted at a third position. The broken lines are for the purpose of illustrating portions of the camera and form no part of the claimed design.

The camera is shown with a symbolic break in its length. The appearance of any portion of the article between the break lines forms no part of the claimed design.
